ATTORNEY

UNITED STATES PATENT OFFICE

133,440

DESIGN FOR A SUPPORTING BRACKET FOR A POT OR THE LIKE

Bestor Robinson, Oakland, Calif.

Application June 9, 1942, Serial No. 107,167

Term of patent 3½ years

(Granted under the act of March 3, 1883, as
amended April 30, 1928; 370 O. G. 757)

To all whom it may concern:

Be it known that I, Bestor Robinson, a citizen of the United States, residing at Oakland, California, have invented a new, original, and ornamental Design for a Supporting Bracket for a Pot or the like, of which the following is a specification, reference being had to the accompanying drawing, forming part thereof.

Fig. 1 is a perspective view of a supporting

bracket for a pot or the like, showing my new design;

Fig. 2 is a top plan view; and

Fig. 3 is a side elevational view thereof.

I claim:

The ornamental design for a supporting bracket for a pot or the like, as shown.

BESTOR ROBINSON.

CERTIFICATE OF CORRECTION.

Design No. 133,440.

August 18, 1942.

BESTOR ROBINSON.

It is hereby certified that error appears in the printed specification of the above numbered patent requiring correction as follows: In the heading to the printed specification, lines 7 and 8, strike out "(Granted under the act of March 3, 1883, as amended April 30, 1928; 370 O. G. 757)"; and that the said Letters Patent should be read with this correction therein that the same may conform to the record of the case in the Patent Office.

Signed and sealed this 15th day of September, A. D. 1942.

(Seal)

Henry Van Arsdale,
Acting Commissioner of Patents.
